(57) **CLAIM**

The ornamental design for an air ratchet tool handle, as
shown and described.

DESCRIPTION

FIG. 1 is a top view of an air ratchet tool handle showing our
new design;

FIG. 2 is a left side view of FIG. 1;

FIG. 3 is a bottom view of FIG. 1;

FIG. 4 is a right side view of FIG. 1;

FIG. 5 is a rear view of FIG. 1; and,

FIG. 6 is a front view of FIG. 1.

The structural features depicted by means of broken lines in
the drawing figures have been shown for illustrative pur-
poses only and form no part of the claimed design.
